UNITED STATES PATENT OFFICE

153,130

DESIGN FOR A TOOTHBRUSH

Howard L. Fischer, St. Paul, Minn.

Application March 26, 1947, Serial No. 137,895

Term of patent 14 years

(Cl. D9—2)

To all whom it may concern:

Be it known that I, Howard L. Fischer, a citizen of the United States, residing in St. Paul, county of Ramsey, and State of Minnesota, have invented a new, original, and ornamental design for a Toothbrush, for which the following is a specification, reference being had to the accompanying drawings, forming part thereof.

Figure 1 is a side elevational view of a toothbrush, showing my new design.

Figure 2 is a bottom plan view thereof; and Figure 3 is a brush head end view thereof.

I claim:

The ornamental design for a toothbrush, as shown.

HOWARD L. FISCHER.
